UNITED STATES PATENT OFFICE

143,127

DESIGN FOR A CLIMBING TOY FIGURE

Leslie H. Burlin, Valparaiso, Ind., assignor to Milton L. Sturm, Evanston, Ill., doing business as Milton Sturm & Company, Chicago, Ill.

Application May 28, 1945, Serial No. 119,764

Term of patent 3½ years

(Cl. D34—15)

To all whom it may concern:

Be it known that I, Leslie H. Burlin, a citizen of the United States, residing at Valparaiso, in the county of Porter and State of Indiana, have invented a new, original, and ornamental Design for a Climbing Toy Figure, of which the following is a specification, reference being had to the accompanying drawing, forming a part thereof.

I claim:

The ornamental design for a climbing toy figure, as shown.

LESLIE H. BURLIN.
